UNITED STATES PATENT OFFICE.

EMIL E. JOHNSTON, OF POTLATCH, IDAHO.

AUTOMOBILE-FENDER.

1,167,698.

Specification of Letters Patent. Patented Jan. 11, 1916.

Application filed September 2, 1915. Serial No. 43,686

To all whom it may concern:

Be it known that I, EMIL E. JOHNSTON, a citizen of the United States, residing at Potlatch, in the county of Latah and State of Idaho, have invented certain new and useful Improvements in Automobile-Fenders; and I do declare the following to be a full, clear, and exact description of the invention, such as will enable others skilled in the art to 10 which it appertains to make and use the same.

My invention relates to improvements in vehicle fenders, and more particularly to those designed primarily for use upon automobiles.

The object of the invention is to provide a device of the class specified which although being simple, compact, and inexpensive, will be highly efficient and durable and will be 20 operated automatically upon striking of a pedestrian by a bumper disposed in advance of the machine.

To this end, the invention resides in certain novel features of construction and in 25 unique combinations of parts to be herein-after fully described and claimed, the descriptive matter being supplemented by the accompanying drawings wherein:

Figure 1 is a longitudinal section of the 30 invention applied to use showing the normal positions of parts; Fig. 2 is a similar view illustrating the locations of such parts after a pedestrian or other object has been struck; Fig. 3 is a top plan view; Fig. 4 is a horizontal section taken approximately on the line 4—4 of Fig. 2; Fig. 5 is a vertical transverse section as seen on the plane designated by the line 5—5 of Fig. 3; Fig. 6 is a similar view as seen on the plane of the line 6—6 of 40 Fig. 1; Fig. 7 is a third transverse section as viewed on the plane of the line 7—7 of Fig. 3; Fig. 8 is an enlarged longitudinal section partly in elevation, through the plunger and the parts directly associated 45 therewith. Fig. 9 is a detail horizontal section through one side of the frame.

In these drawings which constitute a part of the application and in which like reference characters designate corresponding parts 50 throughout the several views, the numerals 1 indicate a pair of upright hanger bars which are bolted or otherwise secured to the side bars 2 of an automobile, the lower ends of

said bars being provided with vertically elongated yokes 3 receiving slidably therein 55 the front automobile axle 4. The intermediate portions of the hanger bars, carry transversely alined bearings 5 in which the ends of a transverse horizontal hinge bar 6 are loosely mounted, said bar constituting 60 the rear end of an approximate rectangular horizontal frame 7 which, in addition to said bar includes a pair of parallel tubular side bars 8 and a front transverse bar 9 which is preferably tubular for the sake of lightness. 65

Having sleeves 10 and 10' receiving respectively the bars 6 and 9, is a pair of upright bracket plates 11 and 11' which support a pair of parallel longitudinally disposed horizontal track plates 12 whose upper 70 edges are provided with longitudinal laterally projecting flanges 13. Interposed between the track plates 12 and likewise extending from one bracket plate to the other, is a guide rail 14 preferably of tubular 75 formation, the aforesaid bracket plates being shown as provided with bosses 15 projecting into the opposite ends of said rail to reliably hold the same against dislocation.

Disposed above and preferably resting on 80 the track plates 12, is a plunger plate 16 having downwardly extending parallel flanges 17 on its longitudinal edges, said flanges being provided with longitudinal series of spaced openings 19 whereby they constitute 85 rack bars. Obviously, rack bars of common construction could well be used in place of the type shown, but the latter is preferable on account of its ease of manufacture.

In order to prevent dislocation of the 90 plunger plate 16, the inner sides of the flanges 17 thereof are equipped with inwardly extending stops 20 preferably in the form of angular flanges. By this construction, the plate and its rack bars are allowed 95 to slide freely upon the tracks, but the removal of said plate is prevented.

The rear end of the plate 16 is provided with a guide 21 which depends between the two tracks and is provided with a central 100 opening receiving therein the guide rail 14, and surrounding said rail between said guide and the front bracket 11', is a coil spring 22 which is compressed when the plunger member is shifted to its normal position at the front end of the tracks 12. The 105

manner of shifting the aforesaid plunger member to compress the spring will be hereinafter described.

For retaining the plunger member retracted against the tension of the spring 22, an appropriate catch mechanism is employed, said mechanism being shown in the present embodiment of the invention as including a stop shoulder 23 rising from the plunger plate 16 and normally abutting a hook-shaped catch member 24 which is pivotally supported by a rock shaft 25 to which it is secured, the ends of the rock shaft being supported for slight rotary movement in bearings 26 rising from the frame 7. This frame is normally raised as shown in Fig. 1, but when it is lowered, the catch 24 is to be released, thus allowing the plunger member to be projected to in turn project a part of the fender in a manner to be hereinafter set forth. It therefore becomes expedient to provide means for tripping said catch when the frame approaches the limit of its downward movement. To this end, practically any type of normally slack operating members may be provided for rocking the shaft 25 when drawn taut by lowering of the frame, but as typical of the preferred form of such members, the drawing illustrates a pair of crank arms 27 which are secured one to each end of the shaft 25, and a pair of links 28 which are pivoted at their lower ends to crank arms 27 and at their upper ends to the projecting front portions of the side bars 2. Normally, the crank arms and links stand as disclosed in Fig. 1, but when the frame is lowered, they aline as depicted in Fig. 2 and in so doing, rock the shaft 25 to release the catch 29, thus allowing the plunger to be projected.

Assisting in alining the links 28 and crank arms 27, and thereby assisting in suddenly lowering the frame when the supporting means therefor is released, is a pair of springs 29. Although the provision of the springs is preferable, the device would obviously operate to advantage with the same eliminated.

Connected in any preferred manner to the front ends of the bars 2 for rearward yielding movement, is a transverse bumper 30 preferably arched in transverse section, while normally closing the lower side of said bumper is an appropriately shaped bar 31 which is carried by the front ends of a pair of longitudinally shiftable normally retracted arms 32 which are slidable in the tubular side bars 8 of the frame 7, the aforesaid bar 31 being normally held in raised position, and therefore normally supporting the guide frame, by a pair of bolts 33. The rear ends of these bolts are pivotally supported by links 34, while the front ends thereof are normally projected through eyes 35 which depend from the bumper 30

through openings in the bar 31, the bolts in question being positioned beneath said bar as clearly disclosed in Fig. 1. Thus it will be evident that when the bolts in question are withdrawn, the bar 31 and the entire frame will be moved downwardly, thus releasing the catch 24 and allowing the plunger to project the bar 31 forwardly, through the instrumentality of motion transmitting means yet to be described.

The downward and forward movement of the bar 31 lowers an appropriate net 36 whose upper edge is secured within the bumper 30 while its lower edge is connected to said bar, the net being normally housed within the bumper as depicted in Fig. 1.

As a simple means of withdrawing the bolts 33 when a pedestrian is struck by the bumper 30, a rock shaft 37 is mounted upon the front ends of the side bars 2, a pair of rigid crank arms 38 depend from said shaft and are connected at their free ends by links 39 with the bolts 33, and the intermediate portions of said crank arms are pivoted to the rear ends of links 40 which extend rearwardly from the bumper 30. By this construction, when the bumper 30 is moved rearwardly by contact with an obstacle, the links 40 will rock the crank arms 38 rearwardly, and obviously the rear ends of such arms will move a greater distance than the intermediate portions thereof, thereby pulling rearwardly on the links 39 and withdrawing the bolts 33, to allow the bar 31 and the frame to drop. The shaft 37 is equipped with an additional crank arm 41 from which a rod or the like 42 leads rearwardly to a point adjacent the driver's seat, whereby said shaft may be operated manually if desired.

The motion transmitting means between the plunger member and the bar 31 includes a pair of crank pins 43 spaced one from each flange 17, said pins being equipped with operating gears 44 whose teeth are received by the openings 19 in the aforesaid flanges, the gears in question being mounted on a transverse preferably hollow bar 45 which connects the side bars of the frame 7. Extending from the crank pins to a pair of collars 46 which are slidable on the arms 32, is a pair of connecting rods 47, coil springs 48 being preferably disposed between the front ends of the collars and stops 49 on the aforesaid arms. By so doing, when movement of the plunger suddenly rotates the gears 44 and shifts the rods 47 forwardly to project the arms 32 and bar 31, the shock will be absorbed by the springs 48. If desired, additional shock absorbing springs 50 (see Fig. 9) may be interposed between heads 51 on the inner ends of the arms 32 and stops 52 at the front ends of the bars 8.

After the device has once been operated, 130

before returning of the numerous parts to normal position, it is necessary to provide some mechanical means for again compressing the spring 22. For this purpose, a 5 jack screw 53 is rotatably mounted in the lower ends of the bracket plates 11 and 11' and is threaded through a nut 54 having an upstanding projection 55 formed with a central opening receiving therein the rail 10 14. Normally, the projection 55 is positioned immediately in advance of the rear bracket plate 11, whereby to offer no obstruction to the rearward movement of the plunger when the latter is released, but 15 when such plunger is to be moved forwardly to compress the spring 22, an appropriate crank or the like such as that indicated at 56 in Fig. 1 may be applied, thus allowing the nut and its projection to be moved forwardly when the screw 53 is rotated. By so doing, the plunger may be retracted until the catch 24 is applied, after which the nut is again shifted to the rear end of the screw.

25 From the foregoing description, taken in connection with the accompanying drawings, it will be obvious that although comparatively simple construction has been devised for accomplishing the desired results, 30 the invention will be efficient and durable, and will possess a number of advantageous characteristics.

In the drawings, certain specific details of construction have been shown for accomplishing probably the best results, and in the foregoing such details have been described, but it is obvious that I need not be limited thereto otherwise than to the extent to which the appended claims restrict me.

40 I claim:

1. In a vehicle fender, the combination of a normally raised fender member to be lowered and projected forwardly, means for normally supporting the fender member, additional means for releasing the aforesaid means, and normally latent projecting mechanism for the fender member released by the lowering of said member.

2. In a vehicle fender, the combination 50 of a normally raised fender member to be lowered and projected forwardly, means for normally supporting the fender member, additional means for releasing the aforesaid means, projecting mechanism for the fender member, catch means for normally preventing actuation of said mechanism, and catch tripping means for releasing said catch means upon lowering of the fender member.

60 3. In a vehicle fender, the combination of a normally raised fender member to be lowered and projected forwardly, means for normally supporting the fender member, additional means for releasing the aforesaid 65 means, projecting mechanism for the fender

member, a catch for normally preventing actuation of said mechanism, and a flexible catch releasing member adapted to be drawn taut when the fender member is lowered, whereby to release the catch.

4. In a vehicle fender, the combination of a normally raised fender member to be lowered and projected forwardly, means for normally supporting the fender member, additional means for releasing the aforesaid 70 means, projecting means for the fender member including a spring pressed plunger having thereon a stop shoulder, a pivoted catch movable downwardly with the fender member and normally abutting the shoulder 75 to prevent actuation of the projecting means, a crank arm rigid with the catch, and a link pivoted at one end to the crank arm and adapted to have its other end pivoted to a fixed member to release the 80 catch when the fender member is lowered.

5. In a vehicle fender, the combination of a normally raised fender member to be lowered and projected forwardly, means for normally supporting the fender member, additional means for releasing the aforesaid 90 means, projecting means for the fender member including a spring pressed plunger having thereon a stop shoulder, a pivoted catch movable downwardly with the fender member and normally abutting said shoulder 95 to prevent actuation of the projecting means, a crank arm rigid with the catch, a link pivoted at one end to said crank arm and adapted to have its other end pivoted 100 to a fixed member, and spring means in conjunction with the crank arm and the link tending to aline the two for the purpose set forth.

6. In a vehicle fender, the combination of 105 a horizontal bumper movable rearwardly, a bar beneath the bumper adapted to be lowered, a net connected at its upper and lower edges to the bumper and to the bar, means for normally supporting the bar including a bolt to be withdrawn to lower said bar, a crank arm in rear of the bumper and mounted independently thereof, a link connecting the free end of the crank arm and the aforesaid bolt, and an additional link 110 connecting the intermediate portion of the crank arm with the bumper.

7. In a vehicle fender, the combination of a fender member to be projected, a normally retracted spring projected plunger for projecting said member, means for releasing said plunger, a rack bar carried by the plunger, a crank pin having an operating gear meshed with the rack bar, and motion transmitting means between the pin and the 115 fender member.

8. In a vehicle fender, the combination of a frame to be attached to a vehicle, a pair of forwardly shiftable arms carried by the frame and in turn carrying a fender mem- 120 125

ber, a normally retracted spring projected plunger carried by the frame and having a pair of parallel rack bars, a pair of crank pins having operating gears meshed with 5 the rack bars and mounted on the frame, and rods connecting the crank pins and the aforesaid arms.

9. In a vehicle fender, the combination with a horizontal frame to be attached to a 10 vehicle, a pair of forwardly shiftable arms carried by the frame and in turn carrying a fender member, a normally retracted spring projected plunger carried by the frame and including a pair of parallel rack 15 bars, a pair of crank pins having operating gears meshed with the rack bars and mounted on the frame, rods pivoted to the crank pins, and yieldable connections between said rods and the aforesaid arms.

20 10. In a vehicle fender, the combination of a horizontal frame including a front bar and a rear bar, a guide member extending from one bar to the other, a spring projected plunger carried slidably by said member, releasable means for holding the plunger retracted, and a fender member to be projected by the plunger when such means is released.

11. In a vehicle fender, the combination 30 of a horizontal frame including a front and a rear bar, a pair of brackets rising one from each bar, a pair of parallel tracks extending from one bracket to the other, a guide rail between the tracks likewise extending from one bracket to the other, a plunger slidable on the tracks and having a guide receive therein a guide rail, a coil 35 spring surrounding said rail between the guide and one bracket, releasable means to normally hold the plunger retracted against the tension of the spring, and a fender member to be projected when such means is released.

40 12. In a vehicle fender, the combination 45 of a pair of parallel horizontal track plates having laterally extending flanges on their upper edges, a horizontal plate above the track plates having a pair of depending flanges contiguous to the outer edges of the 50 aforesaid flanges and each provided with a longitudinal series of openings, stops secured to the depending flanges and contacting with the other flanges, a pair of crank

pins having operating gears whose teeth project into the aforesaid series of openings, 55 a pair of rods pivoted one to each crank pin, a fender member having connection with said rods, a spring for projecting the plunger plate, and means for normally preventing actuation of said spring.

60 13. In a vehicle fender, a pair of upright hanger bars adapted to be secured to the vehicle and having yokes on their lower ends for the reception of the front vehicle axle therein, bearings carried by said bars, 65 a transverse horizontal bar mounted in said bearings, and a fender carrying frame carried by said horizontal bar.

14. The combination with an automatic 70 fender mechanism having an operating spring; of a screw jack formed as a part of the aforesaid mechanism and designed for normally placing the aforesaid spring under tension.

15. In a vehicle fender, the combination 75 of a pair of spaced brackets, a pair of parallel tracks extending from one bracket to the other, a plunger mounted slidably on the tracks, a fender member to be projected by the projection of the plunger, a spring 80 for projecting said plunger, a screw extending from one bracket to the other and rotatably supported thereby, a nut through which the screw is threaded, and a projection on the nut adapted to bear against the 85 plunger, whereby the plunger may be retracted against the tension of its spring by rotation of its screw.

16. In a vehicle fender, the combination of 90 an elongated guide member, a plunger carried slidably by said member, a fender member to be projected by projection of the plunger, a spring for projecting said plunger, a screw parallel to the guide member, a nut through which the screw is threaded, and a projection on the nut for contact with the plunger, 95 whereby the latter may be retracted against the tension of its spring by rotation of its screw.

In testimony whereof I have hereunto set 100 my hand in presence of two subscribing witnesses.

EMIL E. JOHNSTON.
